UNITED STATES PATENT OFFICE.

HENRY E. WEBER, OF CANTON, OHIO.

DESIGN FOR A FOUNTAIN-CUSPIDOR.

SPECIFICATION forming part of Design No. 32,005, dated December 19, 1899.

Application filed November 23, 1899. Serial No. 738,111. Term of patent 14 years.

To all whom it may concern:

Be it known that I, HENRY E. WEBER, a citizen of the United States, residing at Canton, in the county of Stark and State of Ohio, have invented a new and useful Design for Fountain-Cuspidors, of which the following is a specification.

The invention relates to a new and original design for fountain-cuspidors; and it consists of a design of the configuration and ornamentation shown in the accompanying drawings, in which—

Figure 1 is a side elevation of the cuspidor, and Fig. 2 is a vertical sectional view.

The leading feature of the design comprises the bowl 1, the upper end of which is turned

downward within the bowl and the bottom of which is formed with an annular depending bulge 2 and a central downwardly-extending nipple 3, the upper end of which is in a plane 20 above the annular bulge in the bottom.

What I claim is—

The design for a fountain-cuspidor, substantially as herein shown and described.

In testimony whereof I have hereunto set 25 my hand in the presence of two subscribing witnesses.

HENRY E. WEBER.

Witnesses:

CHAS. R. MILLER,
MAMIE MANLEY.
